UNITED STATES PATENT OFFICE.

EDGAR W. UPTON, OF PEABODY, MASSACHUSETTS.

DESIGN FOR A CASE FOR MECHANICAL THERMOMETERS.

SPECIFICATION forming part of Design No. 16,989, dated November 16, 1886.

Application filed June 29, 1886. Serial No. 206,660. Term of patent 7 years.

To all whom it may concern:

Be it known that I, EDGAR W. UPTON, a citizen of the United States, residing at Peabody, county of Essex, and State of Massachusetts, have invented and produced a new and original Design for Thermometers, of which the following is a specification, reference being had to the accompanying drawings, forming part thereof.

10 Figure 1 of the drawings shows my newly-designed thermometer in face view, and Fig. 2 a side elevation thereof.

15 My newly-designed mechanical thermometer comprises a cylindrical or tubular shell provided with a dial or face having a circular opening and a bridge arranged across said opening on the outside, as I will now proceed to set forth.

20 Referring to the drawings, *a* designates the tubular or circular shell; *b*, the face or dial; *c*, the usual pointer employed in mechanical thermometers; *d*, the bridge or bar for said

face; *e*, the circular opening in said face; *e'*, part of the mechanism contained within the case; but the pointer and pinion form no part 25 of my design.

Heretofore thermometer-cases have been made circular, their frame being of ogee shape in cross-section, and their faces showing the dial and pointer.

30 What I claim is—

The design for a case for mechanical thermometers, consisting of the cylindrical or tubular shell *a*, the dial or face *b*, the opening *e* in said dial, and the bridge *d* crossing said 35 opening on the outer surface of the face or dial, substantially as shown and described.

In testimony whereof I have signed my name to this specification in the presence of two subscribing witnesses.

EDGAR W. UPTON.
